UNITED STATES PATENT OFFICE.

ERASmus O. PEOPLES, OF ALLEGHENY, PENNSYLVANIA, ASSIGNOR TO THE NATIONAL CASKET COMPANY, OF SAME PLACE.

BURIAL-CASKET.

SPECIFICATION forming part of Letters Patent No. 629,090, dated July 18, 1899.

Application filed October 12, 1898. Serial No. 693,294. (No model.)

To all whom it may concern:

Be it known that I, ERASmus O. PEOPLES, of Allegheny, in the county of Allegheny and State of Pennsylvania, have invented a new and useful Improvement in Burial-Caskets, of which the following is a full, clear, and exact description, reference being had to the accompanying drawings, forming part of this specification, in which—

10 Figure 1 is a side elevation of an uncovered burial-casket, the left-hand half being in section. Fig. 2 is a longitudinal section showing in full lines the side and end panel and cove-sections folded down around the base of the casket, and in dotted lines the side and end panels raised and the cove-sections only folded back. Fig. 3 is a detail of the lock at the corner of the end and side panels. Fig. 4 is a vertical section on the line IV IV of Fig. 3. Fig. 5 is a plan view of the burial-casket, showing the parts in position to remove the cover. Fig. 6 is a plan of the left-hand end of Fig. 2. Fig. 7 is an end view of the casket; and Fig. 8 is an end view showing the front panel and cove-section and one end panel and cove-section folded down, the back and end panels elevated, and their cove-sections folded outwardly.

My invention relates to burial-caskets; and 30 it consists in providing the body of the casket with hinged side and end panels and cove-sections hinged to the side and end panels. The base portion of the body of the casket is completely hidden from view when the hinged portions are folded down in their lowermost position. The usual appearance of a casket is thus entirely eliminated. The hinged end panels and coves and side panels and coves permit of many and varied effects not possible here- 35 fore, wherein a portion only of the casket is capable of folding.

It also consists in the construction and arrangement of parts, as hereinafter more fully described, and pointed out in the claims.

40 In the drawings, 2 represents the base of the casket, which may be of any desired design, and extending upwardly from this base are the side panels 3 and the end panels 4. These panels, as shown in the drawings, are rigidly 45 connected to the base 2. The side panels 3

are provided with hinged panel-sections 5, and the end panels 4 are provided with the hinged panel-sections 6. To each of these hinged panel-sections is secured a hinged cove section or molding 7 8 of the desired configuration. 55

A removable cover 9, which may be made very light, owing to the fact that the usual heavy molding is not a part thereof, rests upon and is securely locked in place by the hinged cove-sections when they are folded inwardly. To the under side of the cover at its ends are secured pins 10, which enter recesses in the end cove-sections 8. The side cove-sections 7 and end cove-sections 8 are 65 provided with a suitable latch 11. The hinged sections 5 6 of the panels are also provided with similar latches, which are illustrated in Figs. 3 and 4. When the parts are in the position shown in Fig. 5, the two side 70 cove-sections 7 and one end cove-section 8 are locked together, the cover 9 is placed upon the ledge formed on the cove-sections, and the pins 10 inserted in the recesses formed in the end cove-section 8 to receive them. The 75 open cove-section 8 is then closed, and when the latches on the end section engage with the slotted retaining-plates on the side cove-sections the pins 10 are held securely in the recesses in the end cove-section and the cover 80 cannot be removed until the latches are released. The latches comprise a bell-crank lever 12, having a hook on one arm which engages a slotted retaining-plate 13 when in locked position. The other arm of the lever 85 is provided with a pull-cord 14, which extends through the cove and panel sections to the outside of the casket, as shown, so that the latches may be disengaged.

To prevent the hinged side and end panel 90 and cove sections from folding outwardly or downwardly beyond the desired point, straps or other retaining devices 15 are secured to these parts. The handles 16 are secured to the base portion 2 and are so located that 95 when the sides and ends are folded down they are completely hidden from view and do not obstruct the adjustment of these parts. This location makes a much stronger point of attachment than is possible when secured to the 100

hinged side sections. The usual couch or padded mattress 17 is shown in dotted lines in Figs. 1 and 2.

The advantages derived from a casket constructed in accordance with my invention are many, since a large variety of effects may be produced, it being possible to wholly eliminate all resemblance to a casket when the parts are folded down on both sides and ends. 10 The effect then is that of a couch bordered by upholstery. At the same time it does not unduly expose the body. Between this position and that wherein the sides and end panels are all in the elevated position, the cove-sections only being folded back, as shown in dotted lines in Fig. 2, it is possible to make many combination effects, as each of the side and end panels and cove-sections are movable independently relatively to each other 15 and can be placed in such positions as fancy or necessity requires. For example, in Fig. 8 one side and end panel are elevated and their respective cove-sections folded back and the other side and end panel and cove-sections are folded downwardly to their lowest 20 position.

The fastening for the corners of the panel and cove sections and cover are simple and effective, and in order to lock the casket, so 25 as to make it impossible to open it without breaking, it is only necessary to cut the pull-cords and force them inside of the sections through which they extend. The upholstering and covering greatly enrich the appearance of the casket, and a handsome effect is obtained in every position and adjustment of the parts.

The operation and advantages of my invention will be apparent to those skilled in the 30 art, and while I have shown an urn-shaped casket it is obvious this may be changed, and a greater number of hinged sections and the location of the point at which they are hinged, as well as the fastenings employed 35 at the corners and cover, may be made without departing from my invention, since

What I claim is—

1. A casket comprising a base portion, side and end panels surrounding the same, all of said panels being longitudinally divided into 50 upper and lower sections, the upper sections being arranged to fold outwardly, and folding cove-sections secured to the folding panel-sections, the folding panel and cove sections being arranged to surround and conceal the 55 lower panel-sections and the base when folded outwardly and downwardly; substantially as described.

2. A casket comprising a base portion, side and end panels surrounding the same, all of 60 said panels being longitudinally divided into upper and lower sections, the upper sections being arranged to fold outwardly, folding cove-sections attached to the folding panel-sections, and a separate cover arranged to 65 rest on the cove-sections when closed; substantially as described.

3. A casket comprising a base portion, side and end panels surrounding the same, all of 70 said panels being divided longitudinally into upper and lower sections, the upper sections being arranged to fold outwardly, folding cove-sections attached to the folding panel-sections, corner-fastenings between said folding parts, and a retaining device secured to 75 an end cove-section and arranged to engage and hold the cover when closed; substantially as described.

4. A casket comprising a base portion, side and end panels surrounding the same, all of 80 said panels being longitudinally divided into upper and lower sections, the upper sections being arranged to fold outwardly, cove-sections secured to the folding panel-sections, corner-fastenings between the parts, and a 85 separate cover resting upon the cove-sections when the parts are in closed position; substantially as described.

In testimony whereof I have hereunto set my hand.

ERASMUS O. PEOPLES.
